UNITED STATES PATENT OFFICE

LEON OTTINGER, OF NEW YORK, N. Y.

OPERATING MEANS FOR AUTOMOBILE DOOR LATCHES AND WINDOW REGULATORS

Substitute for application Serial No. 294,113, filed July 20, 1928. This application filed August 18, 1928.
Serial No. 300,424.

This invention relates to operating means for automobile door latches and window regulators, and has for its primary object and purpose to provide certain desirable improvements in the invention as shown and described in my co-pending application for patent Serial No. 282,426, filed June 2, 1928. The present application being substituted for an application filed by me on July 20, 1928, Serial No. 294,113.

In my former application, I have disclosed means whereby a single operating handle may be selectively connected at will, either with the mechanism of the window regulator, or with the door latch actuating means and in which the said connecting means is operated through the medium of a movable button or head associated with the rotatably supported end of the handle arm.

It is an important feature of my present invention to provide means for actuating the relatively movable connecting means which dispenses with the use of such an axially shiftable button or head on the handle end and which is arranged and assembled upon the handle arm in such manner that the handle when connected with the latch actuating means has substantially the same form and appearance as the ordinary latch handle of an automobile door, and when the handle is connected with the window operating mechanism, it has practically the same appearance and structural characteristics of the usual separate operating handle for the window as now commonly provided on motor vehicles.

It is also an additional purpose of my present invention to provide such actuating means on the handle arm for the shiftable connecting means whereby the handle may be connected with the window regulator or the latch mechanism and which will also enable the handle arm to be conveniently used as a "pull to" in closing the door.

In one desirable and practical embodiment of my present improvements, the rotatably supported end of the handle arm is provided with the axially shiftable spindle having means for releasably connecting the same with a part of the latch actuating means and

a part of the window regulator mechanism, as disclosed in my former application and upon the opposite end of the handle arm is mounted a pivotable hand grasp member adapted to be thrown so as to make said handle operative to actuate the latch or the window regulator, through means preferably as now indicated. Within the handle arm and coacting with said member and the spindle means are provided for transmitting movement of said member so as to axially shift the spindle to make the desired connection.

It is also an object of my present invention to provide means for effectively obviating lost motion between the several relatively movable parts carried by the handle and which will operate to prevent their accidental or unintentional movement and prevent metallic rattling noise incident to vibration.

It is also a further general object of the invention to improve the original construction shown in my pending application in the particulars above referred to and which is readily adaptable to such operating handles as now used on motor vehicles with a minimum structural modification thereof and which will enable the handle connecting means to be properly operated by the ordinary purchaser without requiring mechanical manipulations of a more or less involved nature.

With the above and other objects in view, the invention consists in the improved operating means for the door latch and window regulator of an automobile, as will be hereinafter more fully described, illustrated in the accompanying drawings, and subsequently incorporated in the subjoined claims.

In the drawings in which I have illustrated several desirable alternative forms of the essential features of my present improvements, and in which similar reference characters designate corresponding parts throughout the several views,

Figure 1 is an elevational inside view of one of the front doors of an automobile showing the present embodiment of my invention;

Fig. 2 is an enlarged vertical sectional view taken on the line 2—2 of Fig. 1, showing the

condition of the mechanism when the handle is connected to the door latch actuating means;

Fig. 3 is a similar view showing the relative positions of the parts when the operating handle is connected to the window regulator mechanism;

Fig. 4 is a detail sectional view taken on the line 4—4 of Fig. 2;

Fig. 5 is a fragmentary elevation of the end of the handle arm as seen from the outer side thereof with the parts disposed as shown in Fig. 2 of the drawings;

Fig. 6 is a vertical sectional view similar to Fig. 2 of the drawings, illustrating an alternative embodiment of my invention;

Fig. 15 is a sectional view taken on the line 15—15 of Fig. 14; and

Fig. 16 is a similar section taken on the line 16—16 of Fig. 14.

I have shown my invention for the purposes of illustration, applied to the forward left hand door 5 of an automobile of conventional design. The door is provided with a window pane 6 disposed between the outer and inner panels of the door, and supported in suitable grooves in the posts of the door. The pane is adapted to be raised or lowered by mechanism incorporated in my invention.

As in my co-pending application this invention may be equally applied to the rear door of a motor vehicle. The front doors are hingedly mounted at their forward vertical edges while the rear doors are hingedly mounted at their rear edges. It will therefore, be apparent that in the application of the device to one of the rear doors, only a reversal of the arrangement shown in Fig. 1, is required. In both cases of course, the door latch 8 is mounted in a suitable mortise provided in the panel 7 at the vertical free edge of the door. This latch may be of various types now in common use, and includes a suitable casing or housing having guide

means for the spring pressed latch bolt 9. The latch further includes the usual rollback 10 operated by an exteriorly projecting handle 11. The operating mechanism for the latch comprises a pivoted lever 12, 12' adapted to retract the bolt either upon suitable movement of the rollback or through means constituting a part of my invention.

The rollback 10 bears against the upper end of the lever 12 so that upon operation of the exterior handle the lever will be operated to retract the bolt. Said lever is yieldingly held in its normal position in contact with the rollback 10 independently of the latch bolt 9, by means of the expansion spring indicated at 13 surrounding a rod 14 pivotally connected to the upper end of the lever 12, said spring bearing at one of its ends against the lever and at its other end against a part of the latch case in which said rod is suitably supported and guided.

It will be understood as this description proceeds that the novel features of my present disclosure may be readily employed in connection with many different types of window regulators as well as other forms of door latches than that above described. In the present instance, I have shown a more or less well known type of window regulator in which the several parts are operatively mounted or supported upon a stamped sheet metal plate 16 attached to a panel 7 by screws, 17, 17. A peripherally toothed sector plate 18 is rotatably mounted at 19 on the lower end of the supporting plate 16. To this toothed sector, a downwardly extending arm 20 is suitably riveted, the lower end of said arm carrying a suitable roller indicated at 21 moving freely in a channelled guide 22 attached to the lower edge of the window glass 6.

Upon the opposite side of the supporting plate 16 a spiral spring 23 is arranged and has one of its ends secured to the rotatable pivot 19 of the sector 18 while its other end is suitably attached to the plate 16. This spring is placed under tension in the downward movement of the window 6 and aids in the lifting or upward movement of said window.

Adjacent to the upper end of the plate 16 a part 24 is struck from the plane thereof and provides a bearing for the stud shaft of a pinion 25 which is in constant meshing engagement with the teeth of the sector plate 18. This pinion is carried by one part of a spring friction clutch of conventional type indicated at 26 which is mounted within the clutch casing 27, said casing having a flange 28 at one of its ends securely riveted to the supporting plate 16. The other member of this clutch is in the form of a sleeve 29 and for the purposes of my present invention is provided with a ring gear 30 fixed to one end thereof and provided with internal cog teeth 31. The pinion 25 has an axially projecting

part 25' with which the other end of the clutch sleeve 29 is connected.

An arm 32 is riveted or otherwise securely fixed as at 33 to a lateral projection or extension of a ring or annulus 34 which loosely surrounds the clutch housing 27 adjacent to the flange 28 thereof. The arm 32 is provided with an angularly offset part 35 positioned in spaced parallel relation to the ring 34 and beyond the inner end of the clutch 26. The arm 32 extends downwardly at an oblique angle and the end thereof is provided with a flanged stud 36 slidably engaged in the slot 37 provided at one end of the bar 38, the other end of which is pivotally connected with the latch bolt retracting lever 12 as shown at 39.

The bearing 40 for the operating handle is provided at one of its ends with an offset longitudinal extension or flange 41 of substantially semi-circular form riveted at 42 to the inner side of the plate 16. The arm 35 abuts against face 44 of the bearing 40 which prevents longitudinal shifting movement of the ring or annulus 34 upon the wall of the clutch housing 27. It will thus be understood that the arm 32 is supported with its part 35 in concentric relation to the axis of rotation of the pinion 25, by the rotatable bearing engagement of the ring 34 on the clutch casing.

The bearing 40 has a straight uninterrupted bore of the required diameter to receive the reduced end portion 46 of the hub extension 45 on one end of the handle arm 47 to support the same for free rotation. This hub extension 45 of the handle arm is provided with an axial bore 48 of rectangular form in cross section which terminates at its inner end within the end of the handle. The reduced end portion of the hub 45 of the handle is counterbored for a short distance to provide an annular recess 49 providing a stop shoulder 50, the purpose of which will presently appear. This reduced part of the handle end 45 within the bearing 40 is further provided with an annular groove 52 in its periphery for the reception of a locking pin 53 which is adapted for insertion through registering openings in the wall of the bearing 40 and in the wall of a sheet metal escutcheon sleeve 54, which surrounds said bearing and bears at one of its ends upon the upholstery indicated at 55 which covers the inner surface of the door 55 and holds the upholstery tightly against the bearing 40. The other end of the escutcheon member terminates in closely opposed relation to the annular shoulder 46' which is formed by the reduced part 46 of the handle end 45, the external surface of said end of the escutcheon being flush with the surface of the handle end projecting inwardly from the bearing 40. The ends of the pin 53 may be swaged or expanded so that they will have a tight frictional fit in the openings of

the escutcheon, to prevent the pin from working loose. Preferably however, the smaller end of the conical escutcheon 54 will be rotatably connected with the bearing 40 as indicated in Figs. 6 and 11. Any suitable means may be provided for holding the escutcheon member against casual rotation on the bearing, such as the narrow inturned rib or flange 54' on the smaller end of the escutcheon which frictionally engages the walls of a shallow annular groove turned in the periphery of the bearing 40. Thus the escutcheon may be adjusted to position the openings 53' in registering relation with the openings of the bearing to receive the relatively short pin 53, said pin being engaged in the groove 52 on the handle hub and having its ends substantially flush with the outer surface of the bearing 40. The escutcheon member is then turned or rotated on the bearing to position the openings 53' thereof out of line with the pin as shown in Fig. 11 of the drawings so that the pin cannot possibly become displaced and the handle released from its operative position.

Within the rectangular bore of the handle a spindle is slidably mounted. Preferably, though not necessarily, I employ a two part spindle consisting of an outer elongated heavy sheet metal sleeve 56 having a snug sliding fit in the bore 48. This spindle sleeve projects beyond the hub extension 45 of the handle and is freely movable through an opening 57 provided in the part 35. At the inner side of the part 35 a plate 59 is loosely mounted on the sleeve 56 but is nonrotatable with respect thereto. The opposite walls of the sleeve 56 at its outer end are provided with outwardly projecting stop lugs 58 which limit the outward sliding movement of plate 59 on the sleeve. It will be noted that the opening 57 in the part 35 and the plate 59 are of similar eccentric outline, form or shape with respect to the axis of the spindle. While this opening and the plate may be of various shapes, they are preferably provided with opposite, comparatively long, converging edge surfaces which afford an extensive area of contact of the plate 59 against the part 35.

Within the spindle sleeve 56 the spindle part 60 is mounted for relative sliding movement and projects beyond the outer end of the sleeve 56 and through the ring gear 30 into the clutch sleeve 29 and is loosely supported for rotation in the part 25'. Upon this end of the spindle 60 a cog or pinion 61 is fixed or may be integrally formed therewith.

Opposite walls of the spindle sleeve 56 are provided with longitudinally extending slots 90 through which the opposite ends of a transverse pin 91 fixed in the part 60 projects, said pin being located in inwardly spaced relation from the plate 59 and having its ends posi-

tioned within the counter bore 49 of the handle hub 45. A comparatively light coil spring 51 surrounds the spindle sleeve 56 and bears at one of its ends against the plate 59 to 5 yieldingly hold said plate in a normal position in engagement with the stop lugs 58. The other end of this spring is engaged against a washer plate 92 which is interposed between said spring and the projecting ends of the pin 91. Said spring 51 thus also acts to 10 yieldingly resist relative sliding movement between the spindle parts 56 and 60 and holds the ends of the pin 91 in contact with the inner ends of the slots 90.

15 In the position of the several parts as seen in Fig. 2 of the drawings, the spring 51 thus holds the plate 59 in position within the opening 57 and in the plane of the part 35 while the cog 61 on the spindle part 60 is positioned 20 within the clutch sleeve 29 and out of engagement with the teeth 31 of the ring gear 30. For the purpose of shifting the spindle axially relative to the plate 59 to disconnect the outer end of the spindle from the clutch of the 25 window regulator while the plate 59 is out of registration with the opening 57, I provide the spring 48' within the inner end of the bore 48 acting against the end of the spindle 56 to yieldingly urge the same outwardly 30 through the handle end.

It is thus seen that in this normal condition, the handle arm 47 is connected with the actuating arm 32 for the door latch, and as will be noted from reference to Fig. 2 of the drawings, the handle arm is thereby sustained in an upwardly projecting position with respect to its axis of rotation on the bearing 40. Therefore, this handle arm is normally in a 40 non-obstructing position, out of the path of movement of the knee of the operator of the vehicle.

When it is desired to adjust the window 6, the operating handle 47 is disconnected from the latch actuating means and connected with 45 the window regulator mechanism by an inward shifting movement of the spindle in the end of the handle, in substantially the same manner as disclosed in my former application. In the latter however, this movement was 50 effected by means of an exposed button or head fixed to the inner end of the spindle and movable with respect to the handle so that when the connection with the window regulator was made, the said button or head was 55 inwardly spaced from the handle end. In my improved construction, I have entirely avoided this projecting operating button and have provided a means which is substantially entirely concealed within the handle and does 60 not materially alter the appearance of the handle from that which is customarily provided for the operation of such devices.

In one embodiment of this operating means for the shiftable spindle, I provide the handle 65 arm 47 which is preferably longitudinally

curved in the usual way so as to afford adequate space between said handle and the inner side of the door to permit the handle to be used as a "pull to" in the closing of the door, with a member 62 movable with respect to 70 the handle arm and preferably connected therewith by means of the transverse pivot 63. This member is thus pivotally mounted in one end of a longitudinally extending slot or channel 64 open at the side of the handle opposed to the door and communicating at its other end with the inner end of the bore 48 in the rotatably supported end of the handle as 75 clearly shown in Fig. 2 of the drawings.

The pivoted end of the member 62 is formed 80 with an eccentric projection 65 having angularly related faces 66 and 67 respectively connected by the curved or convex surface 68. This member is further formed with a stop shoulder 69 at one end of the surface 68. Said 85 member is also provided with a rod or shank 70 extending radially with respect to the pivot 63 and upon which the hand grasp 71 is 90 loosely engaged for free rotation.

Within the groove 64 of the handle arm a 95 rigid longitudinally curved lever 72 is oscillatably mounted intermediate of its ends upon the transverse pivot pin 73. Longitudinally spaced flanges 75 are struck inwardly from opposite walls of the spindle sleeve 56 100 at its inner end, thus affording an opening through which one end of the lever 72 may project, said end of the lever having constant bearing contact against the opposed faces of the flanges 75. With the other end of this lever the member 62 coacts, and as shown in Fig. 2 of the drawings, said end of the lever 72 is in bearing engagement with the face 66 of said member 62 and opposed to the shoulder 69.

The spring 51, by its expansive pressure 105 against the plate 59 forcing the spindle sleeve 56 outwardly through the end of the handle acts to at all times tightly hold the outer end of the lever 72 in contact with the face 66 and thus maintain the member 62 and hand grasp 71 in longitudinally projecting relation to the handle 47 so that to all appearances, in this position of the parts, said handle member constitutes a prolongation or continuation of the arm 47 and has its outer end positioned more or less closely adjacent to the inner face of the door.

With the handle arm thus connected with the latch actuating means by the engagement of the plate 59 in the opening 57 of the part 35, the handle arm 47 extends vertically upward from its axis of rotation. In order to retract the latch bolt and open the door, in the application of the device as shown in Fig. 1 of the drawings, the handle arm is grasped and pulled rearwardly to the position indicated by the broken line A. The arm 32 is thus swung downwardly, drawing upon the bar 38, and swinging lever 12 to retract the 115 bar 130

latch bolt and disengage its outer end from the keeper or strike so that the door may be swung to its open position.

When it is desired to operate the window regulator, the member 62 is pivotally moved on the end of the handle arm 47 from the position of Fig. 2 to the position shown in Fig. 3 of the drawings. In such movement, the eccentric end portion 65 of the member 62 coacts with the end of the lever 72, the convex surface 68 having a rolling bearing contact against the inner side of the lever end, thus moving the other end of said lever inwardly and sliding the spindle sleeve 56 in the bore 48 of the operating handle. By reason of the pin 91 in the spindle part 60 and the spring 51 interposed between said pin and plate 59, the part 60 is also axially moved as a unit with the sleeve 56 so that as the plate 59 is thus disengaged from the part 35, the cog gear 61 is caused to mesh with the teeth of the ring gear 30. However, in the event that the teeth of said gear are not in proper position for meshing engagement with the teeth 31, the spindle sleeve 56 will be moved relative to the part 60, the spring 51 being placed under compression. Thus after plate 59 has been disengaged from the part 35 by a slight further rotation of the handle 47, proper registration of the teeth of gear 61 with the spaces between the teeth of gear 30 will be obtained whereupon the spring 51 will expand to shift the spindle part 60 to its normal position and thus cause the properly meshed engagement of gear 61 with gear 30. Accordingly it will be evident that in any radial position of the handle 47, its disconnection from the latch mechanism may be effected and without liability of damage to the parts of the mechanism.

When the parts are disposed in such positions as shown in Fig. 3 of the drawings, the axis of the hand grasp 71 carried by the member 62 is then disposed in an angular inwardly projecting position relative to the end of the handle arm 47 and the angular face 67 of the member 62 is in bearing contact against the opposed face of the lever 72, the lever end being constantly urged into tight bearing engagement with the face 67 by the pressure of the spring 48'. The member 71 may now be conveniently grasped and the handle arm rotated in its bearing 40 to raise or lower the window 6 in the usual manner. In this construction, it will be seen that in order to release the connection between the operating handle and the window regulator mechanism and to again establish the connection of said handle with the latch actuating means, it is necessary to return the handle arm 47 to the upwardly extending position from its bearing 40 so that the plate 59 will be positioned to register with the opening 57. However, the hand grasp 71 may be returned to the longitudinally pro-

jecting position of Fig. 2 in any radially extending position of the handle arm 47 with respect to the bearing 40. The spring 48' then acts to instantly force the spindle sleeve outwardly and disconnect the cog 61 from the ring gear 30 while the plate 59 being out of registration with the opening 57 in arm 35 is yieldingly urged against the inner face of said arm by means of the spring 51. This plate has a snug sliding fit on the rectangular spindle sleeve 56 and when the handle arm is thereafter further rotated to dispose the same in the upwardly extending vertical position as shown in Fig. 2, the spring 51 then acts to force the plate 59 longitudinally of the spindle and into the opening 57, such independent movement of the plate being limited by the stop lugs. This outward movement of the spindle under the action of the spring 48' takes place concurrently with the movement of the hand grasp 71 from the position seen in Fig. 3 to the extended position in Fig. 2 and bearing contact is maintained between the flanges 75 on the spindle sleeve and the inner end of the lever 72 so that the other end of said lever will be urged into close contact against the surface 66 of the part 62.

I also provide means for locking the door latch by a movement of the handle arm 47 so that the latch bolt cannot be retracted by operation of the outside door handle, the said locking means being substantially the same as that shown in my former application. Thus the bar 38 adjacent its connection with the arm 32 is provided upon its upper edge with the shoulder 76 and above said end of the bar 38 a stop lug or pin 77 is provided on the plate 16. Thus, when the handle arm 47 is moved in the opposite direction from that necessary to retract the bolt, and to substantially the position indicated by the broken line B, the arm 32 is swung upwardly, and the end of the bar 38 is lifted to position the shoulder 76 in opposed relation to the lug 77 and in the path of movement of said bar. Thus since the retraction movement is transmitted to the latch bolt 9 from the outside handle by the rollback 10 bearing against the upper end of the lever 12, it will be evident that such movement of the lever is prevented, as the slotted end of the bar 38 cannot shift relative to the pin 36. In the normal position of the parts as shown in Fig. 1, the latch bolt may be freely retracted by the outside handle without movement of the inside handle arm 47, since the slotted end of the bar 38 may shift freely on the stud or pin 36. Also it will be noted that if the handle arm 47 is moved to the locking position B while the door is open, the door may be forcibly closed or slammed without injury to the latch mechanism, as the bolt 9 will be repressed into the latch case relative to the lever 12, as the end 125

of the bolt moves over the inclined face of the strike.

The handle arm 47 is yieldingly retained in the locked position B by means of a spring pressed latch pin 77' which engages in a notch or recess 35' formed in the perimeter of the part 35. From reference to Fig. 1 of the drawings, it will be observed that the hand grasp 71 projects above the panel 7 and is visible from the exterior of the door through the window glass 6 so that by observing the angular relation between this hand grasp and the horizontal window sill, it may be ascertained whether or not the latch bolt actuating mechanism is locked.

In Fig. 6 of the drawings, I have illustrated an alternative embodiment of the invention which permits of the disconnection of the handle arm 47 from the window regulator mechanism in any radially projecting position of said handle arm with respect to the bearing 40, at which rotation of the arm may be stopped in the adjustment of the window. In this construction the outer end of the rectangular spindle 56' is provided with a transversely movable rectangular pin 78 which is yieldingly urged outwardly beyond one face of the spindle by the spring 79. The outer end of this pin has an inwardly facing sloping or inclined surface 80 and a relatively short outwardly facing inclined surface 81. The wall of the opening in the part 35 at the inner face thereof has a narrow annular beveled surface 82 and the notch or recess in the part 35 at the upper side of said opening is provided with the inclined base wall 83 extending from the annular beveled surface 82 to the outer face of the part 35. The means for establishing an operative relation between the spindle and the window regulator mechanism is the same as that previously described, but in this construction, I have shown the coil spring 48' interposed between the base of the bore 48 in the end of the handle arm and the opposed end of the spindle, which is of one piece construction, having a reduced outer end to which gear 61 is fixed. The other end of the spindle is provided with the opening 74 having opposed convex faces 75' against which one end of the lever 72 bears.

The lever 72 is mounted in the handle arm and connected with the spindle 56' as before described, but in this construction, the end of the handle arm is bifurcated to receive the pivoted member 62' carrying the hand grasp 71, said member being in the form of a disc and having a circumferential groove or recess 84 extending through an arc of approximately 90°.

Suitable friction washers indicated at 85 are arranged upon the pivot of the member 62 between the opposite side faces of said member and the spaced parts of the bifur-

cated end of the handle arm. The end of the lever 72 is at all times positioned within the notch or recess 84 of the member 62'. When the handle arm is connected with the latch actuating means as shown in Fig. 6 of the drawings, the outer end of the spring pressed pin 78 is engaged in the notch or recess of the part 35, the spring 79 holding the inclined surface 80 of said pin in bearing contact with the inclined surface 83 of said part. Thus, the opposite side faces of said pin have an appreciable area of bearing contact against the opposed side walls of the notch or recess so that upon movement of the handle arm 47, rotation will be transmitted to the arm 32. When it is desired to connect the handle arm with the window regulator, the hand grasp 71 is moved to the position shown in dotted lines in the drawings, and one end wall of the recess 84 engages the end of the lever 72 and moves said lever to the dotted line position, thus drawing the spindle 56' inwardly against the pressure of the spring 48'. The surface 80 of the pin 78 riding upon the inclined surface 83 of the part 35 causes the pin to be forced inwardly against the action of the spring 79 so that said pin is disengaged from the notch or recess and withdrawn from the opening in the part 35 as the cog gear on the spindle extension is moved into mesh with the teeth of the ring gear 30. The handle arm can then be rotated to adjust the window as desired. After such adjustment, and in any radial position of the handle arm, the hand grasp 71 is moved to its longitudinally extending position, thus permitting the spring 48' to act upon the spindle and force the same outwardly.

The inclined surface 81 on the pin 78 will ride upon the annular inclined surface 82 of the part 35 to force the pin inwardly. If the pin is not in line with the notch or recess in the part 35, its outer end will simply ride upon the wall of the opening in said part as the handle arm is swung upwardly to its vertically extending position, and when said pin is in alignment with the notch or recess, the spring 79 will then project the same outwardly into said notch, thereby establishing the connection with the latch actuating arm 32 and sustaining the handle arm 47 in the upwardly extending position relative to its bearing 40.

In Figs. 14, 15 and 16 of the drawings, I have illustrated a semi-automatic means for returning the member 62' and the hand grasp 71 to the normal longitudinally projecting position relative to the handle arm 47 and which may also be more effective in preventing accidental displacement of the hand grasp from this position than the friction washers 85 above referred to. Thus, as shown, the member 62 has one side face thereof recessed to accommodate a coiled spring 130

86 one end of which is fixed to the part 62', and the other end of which is suitably secured to the arm 47. There is also mounted in the handle arm, at one side of the groove 5 or channel 64 a spring pressed pin 87 having a conical end portion adapted for engagement in a correspondingly formed seat or cavity 88 in the periphery of the member 62'. Thus it will be understood that the spring 86 acts to normally project the hand grasp 71 to the longitudinally extending position relative to the arm 47 as shown in full lines in Fig. 6. When moved from this position to the dotted line position, the rotation of the 10 part 62' places the spring 86 under tension and the pin 87 is engaged in the seat or recess 88 and acts to partially counteract the action of the springs 86 and 48'. However, since in this position of the hand grasp for 15 operating the window regulator, a positive hold thereon is maintained in the rotation of the handle arm 47, by the use of the holding pin 87 as an aid in overcoming the action of the springs 86 and 48, the resisting pressure of the hand grasp against the hand of the operator will be practically unnoticeable.

In each of the constructions above described, the parts of the window regulator and the bearing 40 may first be assembled 20 upon the supporting plate 16 and applied to the door together with the latch operating connections. The spindle 56 is independently assembled in the end hub extension of the handle arm 47 and said extension then 25 inserted from the inner side of the door into the bearing 40, the projecting end of the spindle passing through the opening 57 in the part 35 and the cog pinion 61 entering the clutch sleeve 29 while the reduced end 30 of the spindle is engaged in the bore of the part 25'. The handle arm being disposed in the upwardly extending position relative to the bearing, the plate 59 or pin 78 carried by the spindle is operatively engaged with 35 the part 35, thereby connecting the handle with the latch actuating means. It is then only necessary to insert the key pin 53 through the escutcheon plate 54 and into the annular groove 52, thereby rotatably locking 40 the handle end in connection with the bearing 40. It will be apparent that this operative assemblage of the several parts of the device upon the door structure may be very 45 easily and quickly performed by unskilled labor.

By the provision of my new operating means for the slideable spindle as herein described, the exposed surfaces of the handle arm remain smooth and unbroken and may be 50 provided with any suitable surface ornamentation. The handle arm 47 may be used in the ordinary manner as a "pull to" for closing the door, and without danger of the accidental disconnection of the handle from the latch 55 actuating means and its connection to the

window regulator. Also as the handle arm in its normal position extends upwardly above the bearing 40, this arm will never be in the way or constitute an obstruction to the free movement of the operator's knee in the manipulation of the clutch pedal. The hand grasp 71 extending longitudinally from the free end of the handle arm, has the appearance of an ornamental terminal or continuation of said arm. The lever member 72 for 60 translating the pivotal movement of this hand grasp into a rectilinear sliding movement of the spindle is housed within a comparatively narrow groove centrally formed in the handle arm, and as seen in Fig. 9 of the drawings, the edges of this groove at the outer face of said arm are rounded so that in grasping the handle arm, no discomfort will be occasioned thereby. Since the plate 59 is normally urged inwardly by means of the spring 51 to position for connecting the handle with the latch actuating means, after the window regulator has been operated, it is only necessary to start the pivotal movement of the hand grasp 71 towards its longitudinally extended position, such movement of said member being continued by the expansive action of the spring 48'. Thus, the re-establishment of the normal operating connection between the handle and the latch actuating 65 means is semi-automatic. I have particularly referred herein to a preferable mounting and arrangement of the cooperating parts for actuating the spindle 56 and have disclosed several different forms of the pivoted member 70 on the free end of the handle arm for coaction with the lever element 72. It is however, possible that various other alternatives for the described form and construction of these 75 cooperating parts may be devised, as well as other specific means carried by the sliding spindle for selectively establishing the operative connection between the operating handle and the window regulator or latch actuating mechanism. It is accordingly to be 80 understood that in the further practical development of the invention, the privilege is reserved of resorting to all such legitimate 85 modifications in the structural details of the various elements as may be fairly incorporated within the spirit and scope of the invention as claimed.

I claim:

1. In combination with an automobile door 120 latch and window regulator each having an actuating element, a single operating handle therefor rotatably mounted at one of its ends on the door, and means for selectively establishing an operative connection between said handle and the door latch or the window regulator, said means including a spindle rotatable as a unit with the handle and movable in the line of its axis, said spindle having 125 means for releasable connection with the respective actuating elements, said means con- 130

- sisting of an operating member for the window regulator and an operating member for the latch movable relative to each other and rotating as a unit with said spindle, a spring 5 yieldingly urging the latter member in one direction to normally maintain an operative connection between the same and the latch actuating means, and means carried by the handle for moving said spindle in the opposite direction to disconnect the handle from the latch actuating element and establish an operative connection between said handle and the window regulator. 10
2. In combination with an automobile door latch and window regulator each having an actuating element, a single operating handle therefor rotatably mounted at one of its ends on the door, and means for selectively establishing an operative connection between said handle and the door latch or the window regulator, said means including a spindle rotatable as a unit with the handle and movable in the line of its axis, said spindle having means for releasable connection with the respective actuating elements, said means consisting of an operating member for the window regulator and an operating member for the latch movable relative to each other and rotating as a unit with the spindle, a spring 25 yieldingly urging the latter member in one direction to normally maintain an operative connection between the same and the latch actuating means, said handle including an arm projecting laterally from the handle axis, a relatively movable part carried by said handle arm, and means for translating a movement of said part with respect to the handle arm into a sliding movement of said spindle in the opposite direction to disconnect the handle from the latch actuating element and establish an operative connection between said handle and the window regulator. 30
3. In combination with an automobile door latch and window regulator each having an actuating element, a single operating handle therefor rotatably mounted at one of its ends on the door, and means for selectively establishing an operative connection between said handle and the door latch or the window regulator, said means including a spindle rotatable as a unit with the handle and movable in the line of its axis, said spindle having means for releasable connection with the respective actuating elements, said means consisting of an operating member for the window regulator and an operating member for the latch movable relative to each other and rotating as a unit with the spindle, a spring 35 yieldingly urging the latter member in one direction to normally maintain an operative connection between the same and the latch actuating means, said handle including an arm projecting laterally from the handle axis, a relatively movable part mounted on the end of said handle arm, and a lever member pivotally mounted intermediate of its ends upon the handle arm, said part coacting with one end of said member in the movement of said part in one direction to actuate said member, the other end of the lever member being operatively engaged with said spindle to axially move the same and disconnect the handle from the latch actuating element and establish an operative connection between the handle and the window regulator. 40
4. In combination with an automobile door latch and window regulator each having an actuating element, a single operating handle therefor rotatably mounted at one of its ends on the door, and means for selectively establishing an operative connection between said handle and the door latch or the window regulator, said means including a spindle rotatable as a unit with the handle and movable in the line of its axis, said spindle having means for releasable connection with the respective actuating elements, said means consisting of an operating member for the window regulator and an operating member for the latch movable relative to each other and rotating as a unit with the spindle, a spring 45 yieldingly urging the latter member in one direction to normally maintain an operative connection between the same and the latch actuating means, said handle including an arm projecting laterally from the handle axis, a relatively movable part carried by said handle arm, and means for translating a movement of said part with respect to the handle arm into a sliding movement of said spindle in the opposite direction to disconnect the handle from the latch actuating element and establish an operative connection between said handle and the window regulator. 50
5. In combination with an automobile door latch and window regulator, a single operating handle therefor, means for selectively establishing an operative connection at will between said handle and the door latch or window regulator, said means including a movable part having means for releasable connection with parts of the window regulator and latch actuating means respectively, means for rotatably mounting said handle upon the door, said handle having an arm projecting laterally in angular relation to its axis of rotation, and means carried by the handle arm for manual operation independently thereof including an element operatively connected with said part for actuating the latter. 55
6. In combination with an automobile door latch and window regulator, a single operating handle therefor, means for rotatably mounting said handle at one end upon a door, a member mounted in said end of the handle 60

- for movement relative thereto and having spaced means for releasable connection respectively with the door latch and window regulator, and said handle having an arm projecting laterally in angular relation to its axis of rotation, and means mounted upon the handle arm for manual operation independently thereof including an element operatively connected with said movable member to actuate the latter.
7. In combination with an automobile door latch and window regulator, a single operating handle therefor, means for rotatably mounting said handle at one end upon a door, a member mounted in said end of the handle for movement relative thereto and having spaced means for releasable connection respectively with the door latch and window regulator, and said handle having an arm projecting laterally in angular relation to its axis of rotation, a part movably mounted on the end of the handle arm for operation independently thereof, and additional means mounted on the handle arm actuated by said part and operatively connected with said movable member to actuate the latter.
8. In combination with an automobile door latch and window regulator, a single operating handle therefor, means for rotatably mounting said handle at one end upon a door, a member mounted in said end of the handle for movement relative thereto and having spaced means for releasable connection respectively with the door latch and window regulator, and said handle having an arm projecting laterally in angular relation to its axis of rotation, a part movably mounted on the end of the handle arm for operation independently thereof and an additional element carried by the handle arm extending longitudinally thereof having one of its ends engaged by said movable part for actuation thereby upon movement of said part relative to the handle arm, and the other end of said element being operatively connected with said movable member to actuate the latter.
9. In combination with an automobile door latch and window regulator, a single operating handle therefor, means for rotatably mounting said handle at one end upon a door, a member mounted in said end of the handle for movement relative thereto and having spaced means for releasable connection respectively with the door latch and window regulator, and said handle having an arm projecting laterally in angular relation to its axis of rotation, a hand grasp pivotally mounted on the end of the handle arm movable from a longitudinally extending position to an angular position relative to the arm for rotating the handle in the operation of the window regulator, and means mounted on said handle arm operatively connected with said movable member and operated by coacting means on said hand grasp in the pivotal movements of the latter to actuate said member.
10. In combination with an automobile door latch and window regulator, a single operating handle therefor consisting of a handle arm, means for rotatably supporting said arm at one of its ends upon a door, means for establishing an operative connection at will between said handle and the door latch or the window regulator, said means including a spindle axially movable in the rotatably mounted end of the handle, a hand grasp pivotally mounted on the other end of the handle arm and movable from a position in longitudinally extending relation thereto to a laterally projecting position for rotating the handle in the operation of the window regulator, and additional means movably mounted on the handle arm operatively connected with said spindle and coacting with means on the hand grasp whereby said spindle is actuated in the pivotal movements of the hand grasp.
11. In combination with an automobile door latch and window regulator, a single operating handle therefor consisting of a handle arm, means for rotatably supporting said arm at one of its ends upon a door, means for establishing an operative connection at will between said handle and the door latch or the window regulator, said means including a spindle axially movable in the rotatably mounted end of the handle, a hand grasp pivotally mounted on the other end of the handle arm and movable from a position in longitudinally extending relation thereto to a laterally projecting position for rotating the handle in the operation of the window regulator, said handle arm having a longitudinally extending groove therein, a lever fully crumpled intermediate of its ends within said groove, one end of said lever being operatively engaged with said spindle, and means on the hand grasp coacting with the other end of said lever in the pivotal movements of the hand grasp to oscillate the lever and transmit an axial movement to said spindle.
12. In combination with an automobile door latch and window regulator, a single operating handle therefor rotatably mounted at one of its ends on the door, and means for selectively establishing an operative connection between said handle and the door latch or the window regulator, said means including a spindle rotatable as a unit with the handle and movable in the line of its axis, a member carried by one end of said spindle for releasable connection with a part of the window regulator, a latch actuating arm through which said spindle extends having an opening therein provided with opposed edges extending in angular relation to the axis of the spindle, a member rotatable with said spindle and movable axially thereon, stop means limiting the axial movement of

- said member on the spindle in one direction, a spring coacting with said member to yieldingly resist independent movement in the opposite direction and to urge said member to a normal position within the opening of said latch actuating arm to establish an operative connection between said arm and the handle when said handle is rotated to a predetermined position, an additional spring 5 mounted in the handle coacting with the spindle to move the same axially relative to said latter member when the latter is out of registration with the opening in said arm and thereby disconnect the spindle from the 10 window regulator, and means mounted on the handle for axially moving the spindle in the opposite direction to disconnect the same from said latch actuating arm and establish an operative connection between the spindle and the window regulator. 15
13. In combination with an automobile door latch and window regulator each having an actuating element, a single operating handle therefor rotatably mounted at one of its ends on the door and means for selectively establishing an operative connection between said handle and the door latch or window regulator, said means including a two part spindle rotatable as a unit with the 20 handle and movable in the line of its axis, said spindle parts each having a means for releasable connection with the respective actuating elements, means mounted on the handle arm for axially moving said spindle 25 parts as a unit to establish an operative connection of one of said means with one of the actuating elements and simultaneously disconnect the other of said means from the other actuating element, and means yieldably permitting relative axial movement between the spindle parts in the unitary axial 30 movement of the spindle in one direction. 35
14. The combination with a window regulator and a latch, of an operating handle therefor, a pivotable hand grasp thereon, and means actuated by said hand grasp selectively operatively connecting said handle to said regulator or said latch. 40
15. The combination with a window regulator and a latch, of an operating handle therefor, pivotable means associated with said handle, and a spindle actuated thereby selectively operatively connecting said handle to said handle to said regulator or said latch. 45
16. The combination with a window regulator and a latch, of an operating handle therefor, a pivotable hand grasp thereon, and a spindle actuated thereby selectively operatively connecting said handle to said 50 regulator or said latch. 55
17. The combination with a window regulator and a latch, of an operating handle therefor, a pivotable hand grasp thereon, a pivotable lever actuated thereby, and means 55 actuated in turn by said lever selectively op- 60
- eratively connecting said handle to said regulator or said latch. 65
18. The combination with a window regulator and a latch, of an operating handle therefor, a pivotable hand grasp thereon, a 70 pivotable lever actuated thereby, and a spindle actuated in turn by said lever selectively operatively connecting said handle to said regulator or said latch. 75
- In testimony that I claim the foregoing as my invention, and have signed my name hereto.
